UNITED STATES PATENT OFFICE.

GEORGE T. PARR, OF ST. PAUL, MINNESOTA.

FOUNTAIN BRUSH.

Application filed December 2, 1921. Serial No. 519,465.

My invention relates to fountain brushes and has for its object to provide a brush having a receptacle adapted to serve as a handle with a discharge head angularly mounted in relation thereto.

Another object is to provide a valve mechanism issuing outwardly through said angularly disposed head with an operating member for controlling said valve protruding therethrough.

A still further object is to provide the head with holding means for detachably securing a brush on the end of the same.

Another object is to form the receptacle of tubular shape and to construct said head so that the same attaches upon the end of the tube.

A still further object is to form the opening from the valve to the interior of the receptacle in said head of large enough proportion so that any substance passing through the valve cannot clog and so that the device may therefore be readily kept clean.

The full objects and advantages of my invention will appear in connection with the detailed description thereof and are particularly pointed out in the claims.

In the drawings, illustrating the application of my invention in one form:—

Fig. 1 is a part sectional side elevational view of one form of my invention.

Fig. 2 is a fragmentary view similar to Figure 1 showing another method of attaching the brush to the operating head.

Fig. 3 is a sectional view taken on line 3—3 of Figure 2.

In Figure 1 I show a tubular receptacle 10 which may be provided with a bottom 11 formed integral therewith on which bottom 40 may be attached to the same in any suitable manner. The upper end of the receptacle 10 is formed with external threads 12 which may be pressed into the body of said receptacle if the walls of the same are made of 45 relatively thin material or which may be cut into the same as desired.

Secured to the end of receptacle 10 is a head 13 which is formed with an enlarged throat 14 terminating in a threaded lip 15 which is adapted to screw upon the threads 50 12 of the container 10. A gasket 33 seated on one side against a shoulder 34 formed on the interior of throat 14 adjacent lip 15 and seated on its other side against the extreme 55 edge of the receptacle 10 adjacent the threaded end thereof serves to form a fluid

tight connection between head 13 and receptacle 10.

Head 13 is further provided with a neck 16 which issues from and is angularly positioned relative to the throat 14 and receptacle 10 as clearly shown in the drawings. In the remote end of the neck 16 is provided a longitudinal bore 17 through which the material within the receptacle 10 is discharged. This bore 17 near the central portion of neck 16 changes into a conical shaped opening 18 which forms a valve seat for a conical shaped valve head 19. Valve 19 is secured to a valve stem 20 which is slidably positioned in a hole 21 concentrically drilled in neck 16 relative to the opening 18 and the bore 17. The interior of the throat 14 is provided with a chamber 22 which directly communicates with the interior of the receptacle 10 and which terminates in a port 23 communicating with the opening 18 in neck 16 of head 13 near the smaller end thereof.

As may be noted in the figure, valve head 19 is of considerably shorter length than the length of the conical shaped opening 18 but however is of a length sufficient to cover the port 23. When the said valve head is in the position shown in the figure port 23 is closed and the contents of the receptacle 10 confined within the same. When the said valve 19 is projected inwardly towards the bore 17 by sliding the valve straight in the hole 21 the said extreme end of valve head 19 being of less diameter than the bore 17 forms a passageway around the said valve head along which the contents of receptacle 10 may flow, which contents thereby are permitted to discharge through the chamber 22, port 23, 90 through the opening 19 and into the bore 17 of head 13.

For operating the valve 19 I provide a button 24 which is securely attached to the extreme end of valve stem 20 which is positioned in close relation to the receptacle 10 so that the said button may be easily pressed towards the neck 16 by means of the thumb when the said receptacle 10 is grasped in the hand. A coil spring 25 positioned on the exterior portion of valve stem 20 is seated between a shoulder 26 formed on the neck 16 and the inner portion of the button 24. This spring serves to hold the valve head 19 seated along the walls of the opening 18 so that the port 23 is normally closed from communication with the bore 17.

At the end of the neck 16 which has a protruding portion 27 extending outwardly from the major portion of the head 13 I attach a brush 28 which is formed with a body portion 29 having seated in the same a number of bristles 40 which may be attached thereto in any suitable manner. Brush 28 is preferably formed circular although the same may be of any shape as desired. The extreme end of protrusion 27 is provided with threads 30 which are adapted to screw into the center of the body portion 29 as clearly shown. A shoulder 31 formed on protrusion 27 serves to stop the movement of body portion 29 and to hold the said brush 28 in place upon the head 13. For directing the contents of receptacle 10 into the brush proper body portion 29 is formed with the central aperture 32 which communicates with the interior bore 17 of neck 16. It can therefore be readily seen that when the device is grasped by the receptacle 10 which serves as a handle, the brush 28 held downwardly and the button 24 pressed the contents of receptacle 10 may pass through port 23 through the bore 17 and the aperture 32 and directly to the brush proper by means of which the said contents may be uniformly distributed over the surface to which the brush is applied. In forming the brush 28 I preferably construct the same so that the bristles 40 surrounding the aperture 32 come in contact at their extreme end. This prevents the contents of the device from flowing directly out of the brush head 29 when the valve 19 is released, the same instead being absorbed by the bristles and distributed throughout the same so that the entire engaging portion 40 of the brush is thoroughly and uniformly impregnated.

Figure 2 shows another method of attaching the brush 28 to the head 13. In this form the extreme end 35 is formed without threads and is provided instead with an annular groove 36 of semi-circular cross section. A similar groove 37 slightly deeper than groove 36 is formed in the interior of body portion 29 and is adapted to exactly register with the groove 36 when the portion 35 of neck 16 is slipped into the brush 28. A circular spring member 38 is adapted to be positioned within groove 37 and is normally of slightly smaller interior diameter than the diameter of the portion 35 in the groove 36. The brush 28 is applied to the neck 16 by inserting the same over the protruding end 35 which has a beveled portion 39 in the extreme end thereof adapted to engage the spring 38 and to spread the same open expanding said spring within the groove 37. Portion 35 may now be slid further into the head until the said spring 38

snaps into place around the groove 36 in which position brush 28 is firmly held seated against the aforementioned shoulder 31 formed on the neck 16.

My improved invention may be used for a number of purposes where a liquid is desired to be discharged and applied with a brush. The same may readily be used as a cleaning device for cleaning clothes or in a print shop for cleaning type and the like. If desired the device with a slightly different form of brush may be used as a stencil brush. Some of the other uses of the device are shoe brushes, stove brushes, and scouring brushes.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. A fountain brush comprising a receptacle, a head detachably secured to said receptacle, said head being formed with a neck having a cylindrical bore communicating with the exterior, the inner end of said bore terminating in a conical valve chamber, said head being provided with a chamber communicating with the interior of said receptacle, and having a port leading from said chamber directly into said conical valve chamber, said neck being further provided with a hole axially arranged relative to said cylindrical bore and communicating with said conical valve chamber, a valve stem slideable in said hole, a valve head mounted on said stem and adapted to become seated against the walls of said conical valve chamber to close said port from communication with said bore, and a brush positioned upon the extreme end of said neck.

2. A fountain brush comprising a receptacle, a head secured to said receptacle, a neck upon said head having a bore communicating with the exterior, a valve chamber at the inner end of said bore, a port leading from said chamber to said receptacle, said neck having a hole axially disposed relative to said bore and communicating with said chamber, a valve stem slideable in said hole, a valve head mounted on said stem and adapted to become seated against the walls of said chamber to close said port and a brush upon the extreme end of said neck.

In testimony whereof I affix my signature.

GEORGE T. PARR.
